CONVERTIBLE RAILWAY FREIGHT CAR

Charles L. Madden and Arthur J. Hersey,
Minneapolis, Minn.

Application November 26, 1934, Serial No. 754,770

16 Claims. (Cl. 105—376)

Our invention relates to improvements in convertible railway freight cars, particularly the type of box car having double side doors.

An object of the invention is to provide an improved freight car of the present character in which standard practices in general construction and use prevail and in which traveling partitioning means are employed to divide the car into compartments for the use of individual shippers of less than carload lots, another object of the invention being to provide a freight car, as above, in which the partitioning means may be employed as inner closures for the doorways of the car.

15 The invention is especially advantageous in its application to the so-called "automobile" car which has wide and relatively staggered doorways closed by double sliding doors which meet midway of the doorways. Although in great seasonal demand, the "automobile" car is not favored for general use because of the wide double door construction which is more or less ineffective in protecting the freight from the weather and which presents practical difficulties 20 in the application to a car of inner doorway closures as for the shipment of grain. Through our invention, the "automobile" car, like other types of double door cars, is made usable as an ordinary car not only for the shipment of automobiles and other bulky non-perishable freight such as poles, rails and the like, but also for grain and the less bulky freight, even though perishable, such as the general run of packaged goods.

35 In providing one form of convertible car, we employ two traveling partition members, one member at either side of the car, each member being movable from one position to another, one position being that of disuse against the inner side of the car removed from the doorway, another being a position providing an inner closure in back of one of the two doors for the doorway, and still another being a position crosswise of the car and lapping the companion partition member to divide the car into two compartments which are individually accessible at both sides of the car.

40 In providing another form of convertible car, we employ a single traveling partition movable back and forth from a position of disuse against one side of the car to a position dividing the car into two compartments which are individually accessible, through the doorways at opposite sides of the car.

45 55 In the drawings, Fig. 1 is a vertical transverse

sectional view of a railway freight car embodying one form of our invention, said view being taken as on the line 1—1 of Fig. 2; Fig. 2 is a vertical longitudinal sectional view taken as on the line 2—2 of Fig. 1; Fig. 3 is a plan sectional view of the embodiment of our invention shown in Figs. 1 and 2, the partitioning member or panels being shown in full lines in positions forming a partition across the interior of the car; Fig. 4 is a fragmentary plan sectional view generally corresponding with a portion of Fig. 3 and showing one of the partition panels in two of the positions occupied thereby; Fig. 5 is a view similar to Fig. 4, the partition panel being shown in still another of the positions into which it is movable; Fig. 6 is a view similar to Fig. 2, the same being a vertical longitudinal sectional view of a car embodying an alternate form of our invention in which a single panel constitutes the partition; Fig. 7 is a vertical transverse sectional view of the car shown in Fig. 6, the same being taken as on the line 7—7 of Fig. 6; Fig. 8 is a detail sectional view of one of the car door locks, the same being taken as on the line 8—8 of Fig. 6; Fig. 9 is an elevational view of the 25 lock shown in Fig. 8; Fig. 10 is a fragmentary plan sectional view of the form of our invention shown in Figs. 6 and 7; Fig. 11 is a detail view corresponding with a portion of Fig. 10, the single partitioning panel being shown in retracted position; Fig. 12 is a vertical sectional view in detail taken as on the line 12—12 of Fig. 1 and showing principally a carrier for a partitioning panel, a portion of the carriage being broken away to reveal otherwise hidden construction; Fig. 13 is a detail sectional view taken as on the line 13—13 of Fig. 12; Fig. 14 is an elevational view in detail of one of the locks at the bottom of a partitioning panel; Fig. 15 is a detail sectional view taken on line 15—15 of 30 Fig. 14 and Fig. 16 is a perspective view in detail of a panel shoe.

35 Reference being had to the drawings, it will be seen that the car structure proper, as shown in both of the illustrated adaptations of our invention, consists of a standard form of box car construction having a floor 20, side walls 21 and a roof 22 supported by carlines 23. At the sides of the car are doorways 24, each doorway being provided with double sliding doors 25, 26 which, when 40 closed, meet at the middle of the doorway. The door 26 of each pair of doors carries a post 27, which, in the closed position of said door, is releasably anchored to the doorway frame in any suitable manner. The doorways 24 are relatively 45

staggered, each being equally offset from the middle of the car longitudinally thereof. The door 26 of each pair and upon which the post 21 is carried slides toward the near end of the car upon 5 the opening of said door. Thus, the post equipped door 26 at one side of the car slides open in a direction opposed to that of the post equipped door 26 at the other side of the car. The two doors 25, 26 of each pair are releasably secured 10 together by the conventional hasp lock 28 which may or may not be sealed in the usual manner, it being our purpose to seal the two doors of each pair individually. Accordingly, we provide a door locking and sealing device 29 for each door, 15 the construction of which is shown in detail in Figs. 8 and 9. Near the bottom of each of the doors 25, 26 is an outwardly projecting eye 30 which is received in an opening 31 of the vertically hinged leaf 32 of a hasp 33, said hasp being secured to the lower track 34 upon which the door slides. Above the eye 30 is a lock pin 35, said pin being slidable vertically on a mounting bolt 36 and adapted to be passed through the eye 30 and over the hasp leaf 32. Thus positioned, the pin 35 keeps the hasp leaf 32 in position 20 embracing the eye 30 with the result that the door is held closed by said hasp. Near its lower end, the pin 35 is formed with a small transverse bore (not shown) to receive the sealing wire 37 of a seal 38 which is employed to protect the door 25 against being opened by anyone without authority.

In the form of our invention shown in Figs. 1-5, the car structure is supplied with a pair of 35 traveling partitioning panels 39. Each panel has an overhead carrier 40 therefor including a rail 41 (Figs. 12 and 13), I-shaped in cross section. This rail structure affords upper and lower tracks at either side of the upright web, said rail being 40 suspended from carlines 23 through a number of hangers 42. Mounted on each rail 41 is a carriage 43 consisting of a frame 44 formed with 45 standing yoke arms 45 arranged in pairs at the opposite ends of said frame. Mounted on and at the inner sides of the yoke arms 45 are flanged 50 wheels 46, the two wheels of each set rolling between the upper and lower tracks of the rail 41 at opposite sides of the web. The rails 41 are correspondingly arranged at the opposite sides of 55 the car, each being opposite the adjacent portion of its respective doorway 24 which is closed by the post equipped door 26. Each partitioning panel 39 is swivelly suspended from its respective carriage 43 by means of an upright hanger stud 55 47 (Fig. 12) revolvably mounted in the carriage frame 44 at the center thereof, the lower end of said stud being secured to a hanger clip 48, which, in turn is fastened by rivets 49 to the panel 39 at its upper margin near an upper corner of the 60 panel. Near the diagonally opposite corner of the panel is a shoe 50 (Fig. 16), said shoe having an upright shank 51 which is riveted to the panel to hold the shoe in place thereon. This shoe is adapted to ride on and slidably support the panel 65 at the floor of the car.

Figs. 3 to 5 illustrate various positions in which a panel 39 may be disposed. In Fig. 4, one of the panels 39 is shown in solid lines in retracted position flatwise against the side wall 21 of the car 70 and removed from the doorway 24, this being the position assumed by said panel when it is not in use. Fig. 5 shows one of the panels 39 in position forming an inner closure for that portion of the doorway 24, which is closed from the outside by 75 the post equipped door 26. In using the panels

39, as in the position shown in Fig. 5, they serve as inner weather doors and make the car more readily usable for standard shipments of the less bulky perishable freight. With said panels 39 disposed as just mentioned (Fig. 5), the car is 5 also conveniently adapted for use in standard grain shipments. In such case, the usual grain door boards 52 (dotted lines) would be employed to supplement the panels 39 and provide inner closure for those portions of the doorways 24 not 10 covered by said panels. In applying such grain door boards 52 to a doorway, the ends thereof, at the middle of the doorway, would be snugly received between the door post 21 and the panel 39 and would require little if any nailing. In Fig. 3, 15 the panels 39 are shown in solid lines in positions wherein they overlap at their free margins and cooperate to form a car dividing partition.

The following provision is made for releasably securing the partitioning panels 39 in the several 20 above described positions thereof. Each panel 39 at each corner, except the upper corner attached to the panel supporting carriage 43, is supplied with an upright lock bolt 53 (Figs. 14 and 15) 25 slidably mounted in vertically spaced guides 54 riveted to a marginally inset portion 55 of the panel. The inner end of each bolt 53 is turned at right angles to the bolt proper to provide a handle 54 for sliding the bolt 53 to retract it from and project it into locking position. A 30 rafter stay 56 for each panel, secured to carlines 23 of the car, is formed with an opening therein (not shown) to receive the end of the projected upper bolt 53 of its respective panel. Two pairs 35 of floor sockets 57, one pair for the two lower lock bolts 53 of each panel, receive the projected lower bolts 53 and together with the upper bolts 53 and the carriers 40 secure the panels 39 in partition forming relation. The functioning of each carrier 40 as a panel securing medium, is brought 40 about by the construction shown in Fig. 12. There it will be seen that a stop block 58 is fastened to the rail 41. One of the wheels 46 of the carriage 43 abuts against this block, while a spring pressed pawl 59 on the carriage frame 45 44 abuts against an opposing shoulder of a cam-stop 60 at the lower side of the rail. Through this construction, the carriages 43 are held immovable in the positions occupied thereby when their respective panels are disposed in partition 50 forming relation. Thus, the lock bolts 53 are assisted by the carriers 40 in securing the panels 39 in position forming a dividing partition for the car. Each bolt 53 may be held and sealed in its projected locking position by turning the handle 54 thereof between spaced keeper lugs 61 (Figs. 14 and 15) fastened to the panel 39 and by threading the wire 62 of a seal 63 through aligned apertures in said lugs. In sealing the lock bolts 53, the panels 39 are guarded against 60 being moved from their partition forming position without authority. The lock bolts 53 at the lower corners of the panels 39 directly beneath the carriages 43 have a function other than that of securing the panels in place. They also 65 serve as lower hinge pins for their respective panels, the axis of each such bolt being in coincidence with the axis about which its panel swivels in its carriage frame. In this disposition of said lower bolts 53, the panels 39 may be released for free swinging movement into position 70 across the car or back to the sides of the car by simply releasing the upper bolts 53 from the rafter stays 56 and the corresponding lower bolts 53 from their floor sockets 57. 75

In the partitioning position of each panel 39, the hinged margin thereof overreaches the post 27 of its respective post equipped door 26. It is to be noted, however, that this post equipped door 26, upon being opened, carries its post 27 away from the panel, wherefore said door 26 as well as its companion door 25, may be opened without being interfered with by said panel.

Upon swinging the panels 39 back to the sides 10 of the car, they take temporary positions, corresponding with the position of the panel 39 shown in dotted lines in Fig. 4, from which temporary positions they are slid into the previously described closure positions of which an illustration 15 appears in Fig. 5. Prior to the sliding of a panel 39 from its temporary position (dotted lines Fig. 4) to its closure position (Fig. 5), the pawl 59 of its carriage 43 is released from the coacting cam stop 60 and the lower hinging lock bolt 20 53 withdrawn from its floor socket 57 (Fig. 4). Proceeding with the sliding of the panel, the lower margin thereof is directed into a channel 25 guide 63 at the floor of the car, the pawl 59 on the carriage 43 being at the same time guided into a notch 64 (Fig. 12) formed between the facing shoulders of opposed cam stops 65, 66 provided at the lower side of the rail 41. When said pawl 59 enters said notch 64, the panel 39 is caught in its closure forming position (Fig. 30 5) and held in that position through the carrier 40 and channel guide 63 and also through the panel hinging lock bolt 53, such bolt at such 35 time being projected into a socket 67 (Fig. 4) in the floor of the car. When it is desired to further move the panel 39 into fully retracted position (solid lines, Fig. 4) the carriage pawl 59 is released from the cam stops 65, 66 on rail 41 and the panel hinging lock bolt 53 is withdrawn from its coacting floor socket 67 (Fig. 4). Thereupon, the panel 39 may be slid into its 40 retracted position of disuse. A stop block 68 (Fig. 2) on the rail 41, like the aforesaid block 58 (Fig. 12), limits the retracting movement of the panel 39 and a cam stop (not shown) on said rail, similar to the cam stop 60 (Fig. 12), cooperates with the carriage pawl 59 releasably to hold the carriage 43 in retracted position against said stop block 68. Thus, the carrier 40 at the top and the channel guide 63 at the bottom secure 45 said panel 39 in retracted position.

In the form of our invention shown in Figs. 6, 7, 10 and 11, a single partitioning panel 69 is employed. This wide single panel 69 has two carriers 70, 71, the same being generally similar to the carriers 40 in the form of our invention first described, but differing in some respects in the form and arrangement of the overhead rails. In the carrier 70, a straight rail 72 is disposed longitudinally of the car directly opposite that portion of the adjacent doorway closed by the door 25. A single channel guide 73 is arranged at the floor at the same side and same end of the car as said rail 72. A portion of the rail 74 of the other carrier 71 superimposes the end portion of the channel guide 73 remote from the adjacent doorway, another portion of said rail 74 extending across the car. With the carriages 75 of the carriers 70, 71 disposed as shown in Fig. 10, the panel 69 is suspended in partitioning position in a vertical plane passing through the meeting lines of the double doors at the sides of the car. In this disposition of the panel 69, each upright margin thereof stands in the reentrant angle between the door 25 and the post 27 on the companion door 26. Either door, therefore, of either pair may

be opened without interference by the panel 69 in its partitioning position. The reach of the rail 74 extending across the car is for the greater portion thereof curved in an arc struck from the swiveling axis of the carriage 75 of carrier 70 in that disposition of said carriage supporting the panel 69 in partitioning position. The panel 69 is shifted from its partitioning position (solid lines, Fig. 10) into its retracted position of disuse (Fig. 11) by first swinging said panel into the position shown in dotted lines in Fig. 10 and then moving the panel on both rails 72, 74 to fully retract it. In shifting said panel 69 from its retracted into its partitioning position, this operation is reversed. The carriages 75 are releasably secured to their respective rails 72, 74 in the said two positions of said panel 69 in the same manner that the carriages 43 are releasably secured to the rails 41 in the first described form of our invention. And the lower end of the panel 69 is 20 releasably secured to the floor 20 of the car in partitioning position, by locking bolts 76 as in the cases of the panels 39 of said first described form of the invention.

In both of the described forms of our invention, 25 the partitioning panels may be retracted into positions of disuse, wherein they offer no interference with standard practices in the shipment of carload lot freight and, too, in both forms of the invention, the panels may be readily moved into 30 partitioning position dividing a car into compartments for the shipment by different shippers of less than carload lots, each compartment being accessible at either side of the car, but only to its respective shipper. In the form of the invention employing double partitioning panels, 35 said panels have the additional function of providing inner closures for portions of the doorways.

Through our improvement, double door cars 40 may be put to convenient use in the shipment of goods in less than carload lots to the great financial benefit not only of the railroads, but also of those who ship goods in relatively small quantities, and such cars may be desirably put to 45 standard uses in the shipment of grain and of the less bulky freight including packaged goods even though of a perishable nature.

Changes in the specific form of our invention, as herein disclosed, may be made within the scope 50 of what is claimed without departing from the spirit of our invention.

Having described our invention, what we claim as new and desire to protect by Letters Patent is:

1. A car having doorways at its opposite sides 55 oppositely offset from the center of the car, each doorway having a pair of horizontally sliding doors meeting midwidth thereof, the door of each pair opening toward the near end of the car carrying an inset post adjacent its meeting edge, two partition panels supported for movement into positions of disuse against opposite sides of the car and for movement into partitioning relation, diagonally of the car, substantially in a plane intersecting the meeting lines of the 60 opposed paired doors, the outer upright margins of said panels lapping the opposed door posts, each at the side of its respective post facing the far end of the car.

2. A car having doorways at its opposite sides, 70 each doorway having a pair of horizontally sliding doors meeting midwidth thereof, one door of each pair carrying an inset post adjacent its meeting edge, two partition panels supported for movement into positions of disuse against oppo- 75

site sides of the car and into partitioning positions lapping each other substantially in a plane intersecting the meeting lines of the opposed paired doors, the extreme upright margins of 5 said panels lapping the opposed door posts at sides thereof in the clear of said posts.

3. A car having doorways at its opposite sides, each doorway having a pair of horizontally sliding doors meeting midwidth thereof, one door 10 of each pair carrying an inset post adjacent its meeting edge, and a partition panel supported for movement into and out of partitioning position substantially in a vertical plane intersecting the meeting lines of the paired doors at opposite sides of the car, the opposed upright margins of said panel lapping their corresponding door posts at sides thereof in the clear of said posts.

4. A car having doorways at its opposite sides, 20 each doorway having a pair of horizontally sliding doors meeting midwidth thereof, one door of each pair carrying an inset post adjacent its meeting edge, and a partition panel supported for movement into and out of partitioning position substantially in a vertical plane intersecting the meeting lines of the paired doors at opposite sides of the car, one upright margin of said panel lapping one of the door posts at the side thereof in the clear of said post.

5. A railway freight car having doorways at opposite sides thereof and having double doors for each doorway, two partition panels, two carriers, one for each panel, each carrier including an overhead track, and a carriage thereon swivelly supporting its respective partition panel, each panel being supported by its respective carrier for movement into a position against one of the inner walls of the car and for movement into a position in registry with a portion of said doorway to form an inner closure member therefor, and for movement into another position crosswise of the car to lap the correspondingly disposed companion partition member and divide the car substantially in a vertical plane 40 passing through the meeting lines of the double doors at the opposite sides of the car, and means for securing each of said partition panels in each of their said named positions.

6. A railway freight car having doorways at 50 opposite sides thereof and double doors for each doorway, two partition members, one at either side of the car, each member being supported for movement into a retracted position of disuse against the inner side of the car and into a second position wherein the partition member forms an inner closure for the doorway and into a third position crosswise of the car, wherein it laps the correspondingly disposed companion partition member, and together therewith divides the car substantially in a vertical plane 55 passing through the meeting lines of the double doors at the opposite sides of the car, and means for securing each of said partition members in each of their said named positions.

7. A railway freight car having doorways at opposite sides thereof and having double doors for each doorway, two partition panels, two carriers, one for each panel, each carrier comprising an overhead track, and a carriage thereon swivelly supporting its respective panel, each panel being supported by its respective carrier for movement into a position against one of the inner walls of the car and for movement into a partitioning position crosswise of the car and

lapping the correspondingly disposed companion panel to divide the car substantially in a vertical plane passing through the meeting lines of the double doors at the opposite sides of the car, and devices for releasably securing each of 5 said partition panels to the floor of the car, one such device for each panel being a hinging structure accommodating swinging movements of the panel about its swiveling axis.

8. A railway freight car having doorways at 10 opposite sides thereof and having double doors for each doorway, a partition panel, a carrier for said panel comprising an overhead track and a carriage thereon swivelly supporting the panel, said panel being movable into a position against 15 one of the inner walls of the car and into a partitioning position crosswise of the car substantially in a vertical plane passing through the meeting lines of the opposed double doors, and releasable means for securing the panel in its 20 said partitioning position, said means including a lock for securing the carriage to said track and a lock for securing the panel to the floor of the car, said latter lock accommodating swinging movements of the panel about its swiveling axis. 25

9. A railway freight car having doorways at opposite sides thereof and having double doors for each doorway, a partition panel, a carrier for said panel comprising an overhead track, and a carriage thereon swivelly supporting the panel, 30 said panel being movable into and out of a retracted position against one of the walls of the car and swingable into and out of a position crosswise of the car to divide the same substantially in a vertical plane passing through the meeting 35 lines of the double doors at the opposite sides of the car, and releasable means for securing the panel to the floor of the car, said means accommodating swinging movements of the panel about its swiveling axis. 40

10. A railway freight car having doorways at opposite sides thereof and having double doors for each doorway, a partition panel, a carrier for said panel comprising an overhead track and a carriage thereon swivelly supporting the panel, 45 said panel being movable into a position against one of the inner walls of the car and into a partitioning position crosswise of the car substantially in a vertical plane passing through the meeting lines of the double doors at the opposite sides of the car, and releasable means for securing the panel in its said partitioning position, said means including a lock for securing the carriage to said track and a lock for securing the panel to the floor of the car. 50

11. A railway freight car having doorways at opposite sides thereof and double doors for each doorway, two partition members, one at either side of the car, each member being supported for movement into a retracted position of disuse 60 against the inner side of the car and into another position crosswise of the car, wherein it laps the correspondingly disposed companion partition member and together therewith divides the car substantially in a vertical plane passing 65 through the meeting lines of the double doors at the opposite sides of the car, and means for securing each of said partition members in each of their said named positions.

12. A car having doorways at its opposite sides, 70 each doorway closed by double doors meeting between the sides thereof, separate, complementing, partitioning panels supported for movement into positions of disuse at opposite sides of the car and into complementing partitioning relationship sub- 75

stantially in a vertical plane passing through the meeting lines of the opposed double doors.

13. A car having doorways at its opposite sides, each doorway closed by double doors meeting between the sides thereof, separate, complementing, partitioning panels supported for movement into and out of complementing partitioning relationship substantially in a vertical plane passing through the meeting lines of the opposed double doors.

14. A car having doorways at its opposite sides, each doorway closed by double doors meeting between the sides thereof, a partitioning panel supported for movement into a position of disuse at one side of the car and into partitioning position substantially in a vertical plane passing through the meeting lines of the opposed double doors.

15. A car having door openings at its opposite sides, each door opening closed by double doors

meeting between the sides thereof, a partitioning panel rigid in the direction of its width and wider than the car proper, said panel being supported for movement from a position of disuse unobstructing the interior of the car into partitioning position substantially in the plane of the meeting lines of the opposed double doors and with the ends of said panel projecting into the opposed door openings.

16. A car having doorways at its opposite sides, each doorway closed by double doors meeting between the sides thereof, separate, complementing, partitioning panels supported for movement into and out of complementing partitioning relationship substantially in a vertical plane passing through the meeting lines of the opposed double doors, each panel, in its partitioning relationship, extending into its respective door opening.

CHARLES L. MADDEN.

ARTHUR J. HERSEY.

20
